CLAIM

The ornamental design of a tool and reversing lever, substantially as shown and described.

DESCRIPTION

FIG. 1 is a perspective view of a tool and lever embodying the design of the present invention.

FIG. 2 is a right side elevational view of the tool and lever illustrated in FIG. 1.

FIG. 3 is a left side elevational view of the tool and lever shown in FIG. 1.

FIG. 4 is a back side elevational view of the tool and lever shown in FIG. 1.

FIG. 5 is a front side elevational view of the tool and lever shown in FIG. 1.

FIG. 6 is a top view of a tool and lever illustrated in FIG. 1; and,

FIG. 7 is a bottom view of a tool and lever illustrated in FIG. 1.
